CLAIM

The ornamental design for a component for an electronic device, as shown and described.

DESCRIPTION

FIG. 1 is a top perspective view of a component for an electronic device showing our new design;

FIG. 2 is a bottom perspective view thereof;

FIG. 3 is a front view thereof;

FIG. 4 is a right side view thereof;

FIG. 5 is a rear view thereof;

FIG. 6 is a left side view thereof;

FIG. 7 is a top view thereof; and,

FIG. 8 is a bottom view thereof.

The broken lines illustrate environmental structure and form no part of the claimed design.

The dot-dash broken lines illustrate unclaimed boundaries and form no part of the claimed design.
